UNITED STATES PATENT OFFICE.

ERNEST C. WILCOX AND BURTON L. LAWTON, OF MERIDEN, CONNECTICUT, ASSIGNEES
TO THE CONNECTICUT TELEPHONE & ELECTRIC COMPANY, INC., OF MERIDEN,
CONNECTICUT, A CORPORATION OF CONNECTICUT.

IGNITER MECHANISM.

1,113,850.

Specification of Letters Patent.

Patented Oct. 13, 1914.

Application filed January 16, 1914. Serial No. 812,517.

To all whom it may concern:

Be it known that we, ERNEST C. WILCOX and BURTON L. LAWTON, citizens of the United States, residing at Meriden, New Haven county, State of Connecticut, have invented certain new and useful Improvements in Igniter Mechanism, of which the following is a full, clear, and exact description.

10 Our invention relates to an improved combined timer and distributor for use in connection with electrical ignition and systems.

The object of the invention is to render very compact the entire construction and improve it as to method of assembling and as to details, all of which will be readily seen and understood from a reading of the following description and examination of the accompanying drawings, in which—

20 Figure 1 is a vertical central section of our improved device relatively enlarged. Fig. 2 is a detail view of a part of the device. Fig. 3 is a plan view of certain parts, certain other parts being removed. Fig. 4 is a cross-section on the plane of the line 4—4.

1 is the central arbor or shaft, the lower exposed end of which may be suitably constructed whereby it may be driven from a suitable source of power to be rotated in 30 proper time with the engine with which the timer and distributor is to be associated. The upper part of the shaft is as shown, reduced in diameter, and especially constructed in the manner and for the purposes herein-35 after described.

2 is the timer case or housing which is mounted upon a suitable bearing, in this instance a ball bearing, the balls of which are indicated at 3.

40 4 is the inner ring of the ball bearing which is mounted friction-tight on the shaft 1.

5 is a washer plate mounted on the shaft 1 below the ball bearing sleeve 4, a suitable 45 dust washer 6 of felt or other suitable material being supported by the washer 5.

Directly above the lower bearing just described, and upon the shaft 1, we provide one or more cams 7—7 (see Fig. 4) for operating the timer element.

The timer is located within the case or housing 2 and comprises the two contact

points 8—9. The point 8 is carried upon an insulating block 10 in turn carried by the casing and in the preferred construction the timer point 8 is screw threaded into a block 11 so that it may be adjusted.

12 is a suitable checking device, in this instance in the form of a nut, to facilitate holding the point 8 in its proper position of adjustment.

The side wall of the case 1 has an opening 13 through which a suitable instrument may be passed to turn the point 12 for adjustment, the outer end of the screw threaded body portion of the point in this instance being provided with a screw-driver slot. The block 11 is provided with a suitable binding post 14. The other point 9 of the timer is carried by a breaker arm which is of unique construction. This breaker arm is preferably formed of sheet metal and includes the two spaced side pieces 15—15^a between which is located a roller 16 which is pivotally mounted to turn freely. The one end of the breaker arm is pivotally mounted upon the stud 17 carried by the case while the opposite end carries the point 9, the latter being riveted or otherwise suitably secured thereto. In this instance, the breaker arm is formed of a strip of sheet metal of approximately C-shaped outline. This arm is bent in the middle to form the end plate 15^b which carries the point 9, while the free ends of the breaker arm are mounted upon the post or stud 17 and held thereon by any suitable means such as a cotter pin.

18 is a spring, which in the form shown, is of the outline of a shepherd's crook, the crooked end extends around the end of the breaker arm mounted on the stud 17, the short end of the arm being caught under an abutment 19, located between the upper and lower plates 15—15^a. The long end of the spring 18 is supported by the inner wall of the case 1 and in the preferred form bears against a metallic conductor strip 20 which is electrically connected with the binding post 21.

22 is a slotted opening in the side wall of the case 1 so lined up with the ends of the contact points 8 and 9 that a small file may be passed through said slot 22 and will be guided thereby into proper position be-

tween the ends of the points 8 and 9 so that said points may be smoothed off or brightened up.

23 is a ring which is carried by the case 5 and which has a slot to afford clearance for the base of the binding post 14-21, the length of said slot permitting the said ring 23 to be turned so as to cover and uncover the openings 13-22. The ring 23 may be 10 mounted in any suitable manner so that it may be held against dislodgment, for example, it may simply have a friction-tight fit.

24 is a handle by which the ring 23 may 15 be easily turned.

The upper part of the case 1 is provided with a cover 25 which cover carries a suitable bearing 26, for example, a ball bearing 20 of the annular ring type. The outer ring of the bearing is preferably forced into tight contact with the cover 25, while the inner ring of said bearing may be slid on and off that part of the shaft 1 adjacent thereto.

25 27 is a window in the upper part of the cover 25 which is preferably provided with a transparent covering and through which the contact points 8-9 may be observed.

28 is a stud on the upper end of the case 30 2, the cover 25 having a suitable opening through which the stud 28 may pass so that in putting the cover in place the window 27 will always be positioned properly for the inspection of the contact points. This stud 35 28 is of sufficient length to project well above the cover 25 so that it may be used to set the distributor case, hereinafter explained, in its proper position.

29 is a dust washer standing above the 40 ball bearing 26, while on top of the dust washer 29 is a spring washer 30 comprising a plurality of radial arms projecting from two-spaced hub portions as shown, said spring washer being compressed and held 45 down by a cotter pin or other suitable fastening 31.

The shaft 1 is provided with a longitudinal bore 32 extending from its upper end down to a point adjacent to the lower ball bearing. The lower end of this bore is provided with a lateral duct 33 to convey oil to the lower bearing, the oil being introduced through the upper end of the shaft 1 when the distributor parts are removed, as hereinafter described. To prevent oil from running through the cotter pin passage in shaft 1, we provide a tubular bushing 34. The upper end of the shaft is preferably slabbed off on one side as shown, so as to 50 receive and hold against rotation a head block 35 which carries the distributor brush 36, the latter being preferably formed of a block of carbon forced radially by a spring 37. This distributor brush is in electrical 55 contact through the medium of a spring 38

with a terminal piece 39 which represents one terminal end of the secondary or high tension circuit of the distributor. 40 represents a terminal piece for the other end of the secondary circuit. In this particular 70 instance, the distributor is provided with four terminal pieces corresponding in number to the number of cams 7 on the shaft 1, two of said terminal pieces 40 being actually shown.

41 represents the distributor casing which is, as usual, formed of molded insulating material in which the terminal pieces 39-40 are fixed for assembling by being cast therein. This casing 41 is held snugly upon the 75 cover 23 of the timer case 2 by any suitable mechanism, but our improved holding clip shown in Fig. 2 is by preference provided. This holding clip comprises a spring arm 43 secured in any suitable way as by a screw 80 44 to the casing 41. On the periphery of the timer case 2 is a button 44. The arm 43 is provided with a slot 45 of sufficient size to clear the head of the button 44, the lower edge of the slot snapping under the 85 button head when the spring arm 43 is forced down so as to hold the parts in proper position. To make the arm 43 longitudinally yielding, we provide the U-shaped bend 46 intermediate the length of 90 said spring arm. By this simple expedient the lower slotted end of the arm may yield sufficiently to snap around the button 44. The arm 43 is preferably hinged as at 95.

The head block 35 of the distributor is 100 preferably formed of insulating material cast to the proper shape, and having a central longitudinal passage conforming to the irregular upper end of the shaft 1 upon which it is mounted, so that the said distributor block can be mounted thereon only 105 in one angular position, to wit, the correct position.

48 is an arm projecting laterally from the timer case 2 and by which the relative angular position of the said case and distributor casing 41 may be shifted to advance or retard the spark, the spark occurring in time with the operation of the breaker arm to separate the points 8 and 9 which normally 110 are in contact and are separated momentarily when one of the cams 7 engages the roller 16 and moves it to the circuit breaking position indicated in several views. At such a time it will be observed that the distributor brush 36 is in contact with one or 115 another of the secondary terminal pieces 40 so that the high tension current released at such time will flow through the distributor circuit.

In our improved construction, we preferably form the spring 18 of two strips as shown, one strip being of steel and the other of bronze, the bronze being located on the outside to guarantee effective electrical con- 120

nection with the strip 20. A steel strip is provided to afford the necessary strength, but since steel is liable to rust, we provide the external bronze strip to guard against 5 said rust and to guarantee an effective electrical contact for a long period. The strip 20 is separated or insulated from the surrounding wall of the metal timer case 2 by any suitable means, for example, by a liner 10 or spacer 49.

The brush 36 is preferably mounted directly in a tube 50 of brass or bronze, for example, said tube being cast into head 35, the spring 38 being riveted or otherwise 15 suitably connected with said tube.

What I claim is:

1. In a timer and distributer, a shaft having a cam thereon, a case mounted upon said shaft, said parts being relatively rotatable, 20 two contacts held within said case, said contacts being normally in engagement, with means for intermittently separating said contacts operated by said cam, and an opening in the side of said case laterally of the 25 ends of said contact points to permit a tool to be inserted between said points.

2. In a timer and distributer, a shaft having a cam thereon, a case mounted upon said shaft, said parts being relatively rotatable, 30 two contacts held within said case, said contacts being normally in engagement, with means for intermittently separating said contacts operated by said cam, and an opening in the side of said case laterally of the 35 ends of said contact points to permit a tool to be inserted between said points, and another opening arranged in line with said points.

3. In a timer and distributer, a shaft having a cam thereon, a case mounted upon said shaft, said parts being relatively rotatable, two contacts held within said case, said contacts being normally in engagement, with means for intermittently separating said 45 contacts operated by said cam, and an opening in the side of said case laterally of the ends of said contact points to permit a tool to be inserted between said points, and a cover for said opening mounted on said case.

4. In a device of the character described, a shaft, a cam thereon, two contact points, one fixed and the other movable, an arm carrying said movable contact point, said arm comprising two spaced plates connected 50 at one end, a pivot mounting for the other end of said arm, an anti-friction bearing between said arms arranged for engagement by said cam to move said movable point.

5. In a device of the character described, 60 a shaft, a cam thereon, two contact points, one fixed and the other movable, an arm carrying said movable contact point, said arm comprising two spaced plates connected at one end, a pivot mounting for the other 65 end of said arm, an anti-friction bearing be-

tween said arms arranged for engagement by said cam to move said movable point, and a spring normally operating to move said arm in a direction to move the movable point into contact with the stationary point. 70

6. In a device of the character described, a shaft, a cam thereon, two contact points, one fixed and the other movable, an arm carrying said movable contact point, said arm comprising two spaced plates connected 75 at one end, a pivot mounting for the other end of said arm, an anti-friction bearing between said arms arranged for engagement by said cam to move said movable point and a spring normally operating to move said arm in a direction to move the movable point into contact with the stationary point, 80 said spring comprising two blades, one blade being of spring metal and the other being of a substantially non-corrosive metal of relatively high electrical conductivity. 85

7. In a device of the character described, a timer case, a shaft, a bearing on said shaft, the lower part of said case resting on said bearing, contact points arranged within the 90 case with means for electrically connecting said points respectively with circuit terminals, a movable carrier for one of said points, a cam on the shaft for actuating said movable carrier for making and breaking a circuit through said points, a removable cover plate for the upper end of said case, said cover-plate having an opening therein to facilitate inspection of said points, means for locating the cover in a position to cause 100 said opening to always overlie said points, a distributer housing mounted on said cover, said cover having a center perforation providing a bearing for the upper part of said shaft, a distributer terminal mounted in said 105 distributer housing, and another distributer terminal mounted on the upper end of said shaft with means for preventing said distributer terminal from being placed thereon excepting at one angular position relatively 110 thereto.

8. In a device of the character described, a timer case, a shaft, a bearing on said shaft, the lower part of said case resting on said bearing, contact points arranged within the 115 case with means for electrically connecting said points respectively with circuit terminals, a movable carrier for one of said points, a cam on the shaft for actuating said movable carrier for making and breaking a circuit through said point, a removable cover plate for the upper end of said case, said cover-plate having an opening therein to facilitate inspection of said points, means for locating the cover in a position to cause 120 said opening to always overlie said points, a distributer housing mounted on said cover, said cover having a center perforation providing a bearing for the upper part of said shaft, a distributer terminal mounted in said 125 130

4

distributer housing, and another terminal mounted on the upper end of said shaft with means for preventing said distributer terminal from being placed thereon excepting at 5 one angular position relative thereto, means for holding the cover on said timer case comprising a yielding washer surrounding the shaft and located above said cover and a pin penetrating said shaft above said spring 10 washer.

9. In a device of the character described, a shaft, a timer mounted thereon for rotation and having a bearing in the lower part of the case, a bore in the shaft extending 15 from the upper end downwardly to a point near said bearing, an oil outlet passage from said bore leading to said bearing.

10. In a device of the character described, a shaft, a timer mounted thereon for rotation and having a bearing in the lower part of the case, a bore in the shaft extending from the upper end downwardly to a point near said bearing, a lateral oil passage from 20 said bore leading to said bearing, the upper 25 part of said case comprising a removable cover having a central bearing on said shaft, said cover being adapted to be held in place by a cotter pin passing through the shaft above said cover plate, a bushing, said shaft 30 having a transverse passage for a cotter pin, said passage being bushed.

11. In a device of the character described, a shaft, a cam thereon, two contact points, one of said points being movable relatively 35 to the other, a curved arm carrying said

movable contact point at one end, a shaft mounting for the other end of said arm, an anti-friction bearing between the ends of said arm for engagement by said cam, and a carrier case for said contact elements and 40 said arm, said cam passing freely through said carrier case whereby said case and associated parts may be removed from the cam by longitudinal movement of the former relatively to the latter.

12. In a device of the character described, a timer casing, a shaft, a bearing on said shaft, the lower part of said case resting on said bearing, contact points arranged within the case with means for electrically connecting said points respectively with circuit terminals, a movable carrier arm for one of said points, a cam on the shaft for actuating said movable arm for making and breaking a circuit through said points, a removable 50 cover plate for the upper end of said casing, a distributer housing mounted on said cover plate, the latter having a central perforation providing a bearing for the upper part of said shaft, a distributer terminal mounted in the distributer housing, another distributer terminal mounted on the upper end of the shaft with means for holding said distributer terminal thereon at the desired angle.
